UNITED STATES PATENT OFFICE.

ANDREW W. BISHOFF, OF AMBIA, INDIANA, ASSIGNOR OF ONE-HALF TO
FREDERICK E. HANSON, OF SAME PLACE.

WASHBOARD.

SPECIFICATION forming part of Letters Patent No. 644,760, dated March 6, 1900.

Application filed November 20, 1899. Serial No. 737,686. (No model.)

To all whom it may concern:

Be it known that I, ANDREW W. BISHOFF, a citizen of the United States, residing at Ambia, in the county of Benton and State of Indiana, have invented a new and useful Washboard, of which the following is a specification.

The invention relates to improvements in washboards.

10 The object of the present invention is to improve the construction of washboards and to provide a simple, inexpensive, and efficient one possessing great strength and durability and adapted to have worn portions of its rubbing-15 surface readily renewed by changing the position of the parts.

15 The invention consists in the construction and novel combination and arrangement of parts hereinafter fully described, illustrated 20 in the accompanying drawings, and pointed out in the claims hereto appended.

25 In the drawings, Figure 1 is a perspective view of a washboard constructed in accordance with this invention. Fig. 2 is a longitudinal sectional view. Fig. 3 is a detail sectional view on line 3-3 of Fig. 2. Fig. 4 is a detail sectional view taken transversely of one side of the washboard.

30 Like numerals of reference designate corresponding parts in all the figures of the drawings.

35 1 designates the frame of a washboard, composed of side bars 2, transverse connecting-bars 3, 4, and 5, and a back board or shield 6, arranged at the upper portion of the board and adapted to prevent any water from leaking through the top of the washboard onto the clothes of the operator. The cross-bar 3 is arranged at the top of the washboard, and 40 the bar 5 is located near the lower ends of the side bars. The transverse bar 4 is located at an intermediate point, being arranged at the top of the rubbing-surface in use to form a soap-receptacle.

45 45 The side bars 2 of the frame of the washboard are provided at their inner faces with longitudinal grooves 7, and one of the side bars is provided at its upper end, near the top cross-bar 3, with an opening 8, communicating 50 with the ways formed by the grooves 7 and adapted to permit tubular slats or sec-

tions 9 to be introduced into and removed from the ways formed by the grooves 7. The cross-bar 5 is located at the lower ends of the ways, and it is provided with projections or tenons 10, secured within the same by suitable fastening devices. The tubular slats or sections have straight side edges and are provided with corrugated inner and outer or, rather, front and rear faces 11, forming rubbing-surfaces and adapted to permit the slats or sections to be removed through the opening 8 and turned end for end to reverse them, so that worn portions of the rubbing-surface of the washboard may be renewed. It has been found by experience that with washboards having rubbing-surfaces formed by continuous sheets of zinc or other material the entire washboard must be discarded as soon as any portion of the rubbing-surface becomes worn, as such worn portion is liable to tear the clothes.

55 The tubular slats or sections are filled in the grooves or ways from the bottom bar 5 to the top bar 3, and those forming the bottom of the soap-receptacle and lying above the transverse bar 4 are adapted to be exchanged for those lying below the transverse bar 4 when it is necessary to renew the rubbing-surface in use after both rubbing-faces of the slats or sections thereof have become worn. This construction provides the washboard with a large amount of rubbing-surface adapted to be successfully used and capable of enabling the rubbing-surface in use to be renewed for a long time without discarding the washboard, and a new set of slats or sections may be obtained after those of a washboard have become entirely worn out.

60 The slats or tubular sections, which may be left hollow, are preferably provided with a suitable filling or body 12, of wood or any other material, which may be of a plastic nature in order to be easily run into the slats or sections. The tubular slats or sections are supported by being interlocked, as clearly illustrated in Figs. 2 and 3 of the accompanying drawings, and each slat or section is provided at one edge with a pair of studs or projections 13, and it has at its opposite edge corresponding sockets 14. These projections or studs form tenons and mortises and do not interfere

with the changing of the slats from one part of the board to another.

The slats or sections are firmly held in the grooves or ways of the washboard by clamping-screws 15, extending through perforations of the top bars 3 and engaging the uppermost slat or section 9. The screws also pass through nuts 16, which are secured in recesses of the top bar 3 by plates 17, arranged on the inner 5 or lower face of the top bar, as clearly illustrated in Figs. 2 and 3 of the drawings. The bottom cross-bar 5 is provided with screws 18, having flat ends arranged flush with the inner side of the bar and adapted to prevent the 10 same from being worn away by the slats or sections. The space at the top of the washboard between the top slat and the top bar 3 communicates with the opening 8 and permits the board to drain freely at this point, so that 15 there is no liability of it becoming water-soaked and rotting away.

It will be seen that the washboard is exceedingly simple and inexpensive in construction, that it is strong and durable, and that its rubbing-surface is adapted to be renewed when worn by changing the position of the slats and reversing the same to bring either of their rubbing-surfaces to the front of the board. The space above the slats permits the board 20 to drain freely through the opening 8 when the washboard is inverted, and the intermediate transverse bar is recessed or cut away at its inner face to provide for the drainage of the front of the board.

30 The frame of the washboard is supported at the upper ends of the ways or grooves by a cross-bar 19, arranged in rear of the opening, as clearly illustrated in Fig. 3 of the drawings.

What is claimed is—

1. A washboard comprising a solid rectangular frame provided at the inner faces of its sides with longitudinal ways and having an opening extending entirely through one of the sides and forming an entrance to the ways, a 40 series of reversible and interchangeable slats arranged in said ways and adapted to be removed from and introduced into the same through the said opening, and an adjusting device arranged at one end of the frame and 45 engaging the adjacent slat to hold the slats out of alignment with the opening, substantially as described.

2. A washboard comprising a frame having opposite ways, a series of separate reversible 50 and interchangeable slats or sections provided with interlocking projections and recesses, located at their side edges, and an adjusting device for holding the slats in engagement with one another, substantially as described. 55

3. A washboard comprising a frame composed of side bars provided at their inner faces with grooves, one of the side bars having an opening communicating with its groove, the transverse bars 3, 4 and 5 connecting the side 60 bars, and a back, reversible and interchangeable slats arranged in the grooves and interlocked with each other, and adjusting-screws mounted on the frame at the top thereof and engaging the top slat or section, substantially 65 as described.

In testimony that I claim the foregoing as my own I have hereto affixed my signature in the presence of two witnesses.

ANDREW W. BISHOFF.
